(57) **CLAIM**

The ornamental design for an extrusion welder housing, as shown and described.

DESCRIPTION

FIG. 1 is a perspective view of an extrusion welder housing showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a perspective view of the extrusion welder housing including a welding shoe, a hot air nozzle and grips shown in phantom for more clearly illustrating the environment in which the extrusion welder housing is used. The phantom lines used to depict the welding shoe, hot air nozzle and grips are for illustrative purposes only and form no part of the design.
